DIVISIBLE CARTON

Allen B. Thomas, Rochester, N. Y.

Application May 28, 1949, Serial No. 95,963

4 Claims. (Cl. 229—15)

1

The present invention relates to shipping containers or cartons and particularly to containers or cartons for transporting bottled goods, such as bottled beer.

Bottled beer at the present time is shipped to a large extent in cardboard cartons which are adapted to contain a dozen bottles of beer. Frequently a customer will come into a grocery or a supply store who only wants half a dozen bottles of beer. Heretofore, the dealer or groceryman has had either to refuse to make the sale, or to cut the carton open, take out of it the required number of bottles, and put these bottles in a bag or some other form of container so that they can be carried away by the customer. The breaking open of the carton, removal of the bottles from the carton, and putting them in some other form of container involves time, is inconvenient, is costly, and involves danger of breakage and loss.

It has been proposed to score cartons for transporting beer bottles so that the cartons may readily be cut in two so that half a dozen bottles of beer can more readily be made available for sale to a customer. These half cartons can be used as receptacles in which to carry the half dozen bottles away, but the half carton is somewhat awkward to handle and provides no protection against the bottles dropping out of it.

A primary object of the present invention is to provide an original container which is so scored that it may readily be separated into two independent containers, each forming a suitable receptacle for carrying the bottles or other articles that are contained therein.

Another object of the invention is to provide a divisible carton which may be separated into two sections and in which the two sections have partition members along their original joining parts which prevent the bottles or other articles, which are shipped in the containers, from falling out of the two parts of the carton after these parts are severed from one another.

Still another object of the invention is to provide a carton of the character described having partition members in the adjoining portions of the two parts of the carton which are in the form of straps and which may serve as handles for carrying the separated parts of the carton.

Another object of the invention is to provide a carton of the character described, in which the straps serve not only as handles for carrying the parts of the carton, after severance, but also as dividers or retainers for the contents of

each half of the carton, both prior and subsequent to division of the carton.

A further object of the invention is to provide a carton which has a folding, collapsible, internested, cardboard separator for holding the bottles or other articles and preventing them from rattling around in the carton during shipment, and which is provided with strap members that serve as partitions in the original, whole carton and as carrying members for the severed parts of the carton, and which may be internested with the collapsible, folding separator in such wise as to permit easier insertion of the separator into the carton and easier fastening of the straps to the carton.

Another object of the invention is to provide a carton having strap members of the character described in which each strap tends to wrap itself around the bottles when being used to carry a part of a carton in such wise as to relieve some of the pressure from the staples or other fastening means by which the strap is attached to the carton.

Another object of the invention is to provide in a carton of the character described straps, which serve not only as partitions and handles, by which to carry the halves of the cartons, but also as liners for strengthening the cartons.

Still another object of the invention is to provide a carton for bottled goods, which may be separated to provide a plurality of containers, each containing part only of the number of bottles held in the original carton, and which have strap members for carrying the severed parts of the carton that are attached to each part in such wise that the bottles lie horizontally in that part and do not show above the confines of the container formed by the severed part of the carton.

Other objects of the invention will be apparent hereinafter from the specification and from the recital of the appended claims.

In the drawings:

Fig. 1 is a perspective view of a carton made according to one embodiment of this invention;

Fig. 2 is a perspective view showing the divided carton, the two halves being shown separated from one another, and the outside of one half being broken away to show the interior structure of the carton;

Fig. 3 is a horizontal sectional view through the original carton on a somewhat enlarged scale;

Fig. 4 is a vertical sectional view through the 55 carton taken on the line 4—4 of Fig. 3;

Fig. 5 is a view showing the separator folded, that is, collapsed, and showing how the strap members internest with this separator in folded position; and

Fig. 6 is a view on a reduced scale showing half of a carton with bottles therein and showing how the strap-partition member may be employed as a handle for carrying the receptacle formed from half a carton.

The drawings show a divisible shipping carton C made of fiber or corrugated board and folded to have side walls 10 and end walls 11. The side walls 10 are bent to have upper and lower closure flaps 12. The end walls 11 are similarly bent to have closure flaps 14 along their upper and lower margins. The side wall flaps 12 are adapted to meet, when the box is closed, along the longitudinal center line of the carton; and the end wall flaps 14 terminate short of the transverse center line of the carton. The side wall flaps 12 are adapted to be folded upon and be secured flatwise by adhesive, or in any other suitable manner, to the end wall flaps 14 according to conventional practice.

To prevent the bottles or other articles, which are transported therein, from rattling around in the carton and to keep them separated from one another and from bumping one another, an internesting, foldable separator S is adapted to be inserted in the carton. This separator may comprise the two longitudinally extending partition members 15 and two transversely extending partition members 16. The longitudinally extending partition members are slotted from the bottom upwardly for part of their height as denoted at 17 and the transversely extending partition members 16 are slotted from the top downwardly, as denoted at 18, in conventional fashion so that the longitudinal and transverse members will internest with one another.

Separators used in cartons made according to this invention differ, however, from conventional separators in that instead of having a third transverse partition member between the two transverse partition members 16 shown in the drawings, the longitudinal partition members 15 are provided with centrally disposed downwardly extending slots 19. These slots are adapted to receive two contiguous straps 20.

The straps 20 are made of cardboard in the embodiment of the invention shown. These straps 20 are folded to have transverse portions 21 which extend parallel to the transverse partition members 16, side portions 22, and end portions 23. The end portions 23 extend approximately half way across the width of the carton. The end portions may be connected together by pieces of adhesive tape 24 or may be left free. Each strap member 20 thus encloses and surrounds half of the internesting separator.

In the embodiment of the invention shown, the end portions 23 of the straps are stapled to the ends 11 of the carton by staples 25. The side portions 22 of the strap member might, however, be stapled to the side 10 of the carton if desired.

The slots 19 in the partition members 16 are preferably made deep enough to extend below the tops of the slots 17 in those partition members. This locates the straps 20 nearer to the center of gravity of the carton when filled with bottles. It also leaves only a small portion of each partition member 16 to be torn when the carton is severed in two.

The carton constructed according to the pres-

ent invention can be shipped in knockdown flat form, according to conventional practice, from the carton factory to the glass factory, at which the bottles are made. The internesting of the

5 strap members 20 with the separator S permits the separator with the internested strap members to be shipped in knockdown form also, as shown in Fig. 5. At the glass factory, the carton is opened up; and the underside or bottom flaps are 10 lapped over one another and sealed together. The separator with the straps 20 is opened up and inserted in the opened carton. The straps center the separator and make for easy quick insertion of the separator into the carton in the correct position. The opened separator also centers the straps for stapling to the ends of the carton. The bottles are then placed in the twelve 15 pockets provided by the separator and straps. The top flaps of the carton are then temporarily 20 fastened down; and the carton with the empty bottles therein is then shipped to the brewery. There the bottles are filled. Then the carton with its load of filled bottles is shipped to the dealer.

25 The carton is preferably scored or perforated midway of its length along a line such as indicated at 30 in Fig. 1. If a customer comes in and wants only a half dozen bottles of beer, the dealer can quickly sever the carton in two by 30 passing a knife along the line 30 which lies in the plane of abutment of the transverse portions 21 of straps 20. The partition members 15 are sufficiently weakened by the slots 19 to be broken apart easily when the carton is severed, but if 35 desired they might also be scored in prolongation of the slots 19. The straps 20 hold the bottles in the two severed halves of the carton. Each half of the carton contains half a dozen bottles; and the customer can easily transport the half-40 container by grasping strap 20 attached thereto as shown in Fig. 6, the strap acting as a handle.

It is to be noted that in transportation the bottles lie horizontal. So far as known to me, this is the first bottle carrier in which the bottles 45 are carried in horizontal position. It is further to be noted that the bottles do not protrude beyond the container but lie wholly therein. This is an advantage, particularly with women customers, because they are ordinarily averse to being seen transporting beer bottles.

If the strap members 20 are stapled at their end portions to the ends of the carton, then each strap tends to wrap itself around the bottles in the half-carton when the half carton is lifted, as 55 shown in Fig. 6, thereby taking some of the pressure off of the staples.

The strap members act not only as partitions and carrying handles, but also as liners strengthening the carton, as will be clear from Figs. 3 and 4.

60 The straps 20 may be made of various materials. They can be made of cardboard, as described, or of cloth, leather, plastic, etc. They may also be made of wire with their ends bent, for instance, and passed through the sides of the container and then fastened. Moreover, they can be fastened to the carton halves in any suitable manner or by any suitable means. They can be fastened to the sides of the carton 65 rather than to the ends thereof, if desired; and they may be fastened by a suitable adhesive rather than staples.

If desired, the straps can be colored different colors for different brands of beer.

70 While the invention has been described in con-

nection with cartons for transporting beer bottles, it will be understood that it is not limited to this use. It may be employed in cartons for transporting other bottled goods such as soft drinks, bluing, etc. It may also be employed in the transportation of canned goods. In fact, it may be employed wherever it is desirable to provide a carton which is divisible to permit sale of part of the contents of the carton.

While the invention has been described, therefore, in connection with a particular embodiment thereof and a particular use therefor, it will be understood that it is capable of various modifications and uses, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A shipping container comprising a closed body including top, bottom, and four side walls, a compartmented filler comprising internested longitudinal and transverse partition members, and a pair of straps that abut against one another in a plane transverse of the body and that are secured to the side walls but are free of the filler, said straps being of less height than the side walls, said container and longitudinal partition members of the filler being divisible in the transverse abutting plane of the straps, said straps serving as partition members in the whole container and as handles with which to carry the halves of the container when separated.

2. A shipping container comprising a closed body including top, bottom, and four side walls, a compartmented filler comprising internested longitudinal and transverse partition members, and a pair of straps that are secured to the side walls but are free of the filler, said straps having portions that extend transversely of the container between opposed side walls thereof and fit into slots in the longitudinal partition members of the filler, said container and longitudinal partition members being divisible in a plane between opposed portions of the straps, said straps being of less height than said opposed side walls of the container and serving as partition members in the whole container and as handles with

50
55

which to carry the halves of the container when separated.

3. A shipping container comprising a closed body including top, bottom, and side, and end walls, compartmented filler comprising internested longitudinal and transverse partition members, and a pair of straps that have portions which extend transversely of the container between opposed side walls thereof, each of said straps having other parallel side portions extending along contiguous to said opposed side walls of the container, each of said straps having other portions at the ends of said side portions which extend toward each other and are contiguous to an end wall of the container and are fastened to said end wall, said container being divisible in a plane between the transversely extending portions of the straps, said straps being of less height than said opposed side walls and serving as partition members in the whole container and as handles with which to carry the halves of the container when separated.
4. A shipping container comprising a closed body including top, bottom, and four side walls, a compartmented filler comprising internested longitudinal and transverse partition members, and a pair of straps that are secured to side walls of the container and have portions that extend transversely of the container intermediate the ends of the container parallel to the transverse partition members of the filler, said transversely extending portions of the straps being equi-spaced from the transverse partition members of the filler to form with the longitudinal and transverse partition members of the filler pockets for the articles which are to be shipped in said container, said container being divisible in a plane between the transversely extending portions of the straps, and said straps being of less height than the side walls of the container and serving as handles with which to carry the halves of the container when separated.
